CONTROL MECHANISM

Edward P. Bullard, III, Fairfield, Conn., assignor
to The Bullard Company, a corporation of
Connecticut

Application June 4, 1941, Serial No. 396,544

48 Claims. (Cl. 60—97)

This invention relates to control mechanisms, and particularly to an automatic control mechanism for apparatus including one or more members adapted to be moved by fluid-operated means in either direction along one or more paths at a plurality of speeds.

The principal object of this invention is to provide apparatus having one or more members adapted to be moved by fluid-operated means, the activity of which is initiated by a source of power rendered effective in response to the motion of said members.

Other objects include, the provision of apparatus comprising a member adapted to be moved along a path in either direction at any one of a plurality of speeds by the selective actuation of various means that control fluid-actuated means, and clamp means for normally holding the member against movement but adapted to be released upon the actuation of any of the control means; the provision of a fluid system including a plurality of fluid motors on both sides of which relatively low pressure liquid is adapted to be balanced by a traverse-pressure pump during periods of inactivity so that exhausting selected sides of said motors will permit traverse movement thereof; the provision of such a fluid system in which the traverse-pressure pump supplies liquid to a feed-pressure pump that is adjustable to deliver pre-determined quantities of liquid to selected sides of said motors independently of the pressure encountered in moving the motors, and in which the exhaust from said motors is returned to the inlet side of the feed-pressure pump ahead of the traverse-pressure pump; the provision of a fluid system including fluid-motor means for moving one or more members along one or more paths at a relatively rapid traverse rate and at a plurality of feed rates, in which a time-delay mechanism is provided that may be rendered effective for a pre-determined duration each time the members are moved at rapid traverse rate; and the provision of apparatus comprising a plurality of appliances each including a member adapted to be moved along a plurality of paths by fluid-operated means the activity of which is initiated by a source of power rendered effective by the motion of said members, and in which any member of any of the appliances is capable of rendering effective any of said sources of power.

The above, other objects and novel features of the invention will become apparent from the following specification and accompanying drawings, in which:

Figure 1 is a schematic representation of apparatus embodying the principles of the invention;

Figure 2 is a diagram of a typical operation of the apparatus for turning a work piece to size; and

Figure 3 is an electrical circuit diagram for three sets of apparatus similar to that of Fig. 1, arranged in cooperative relation.

The principles of the invention have been shown schematically in their simplest form, and although they may be applied with equal facility to any apparatus including one or more members adapted to be moved along one or more paths at any of a plurality of speeds, they will be described in connection with apparatus for turning work to size.

This application contains subject matter common to application Serial #353,935, filed August 20 23, 1940, in the name of Edward P. Bullard III.

Referring to Fig. 1, a tool head 160, adapted to support one or more tools 161 is adapted to be reciprocated along ways 162 on a member 163. The head 160 is connected to a rod 164 that extends through a cylinder 165, and a piston 166 is fixed to rod 164 for operation within said cylinder.

The member 163 is adapted to be reciprocated along horizontal ways 167, 168 on a supporting member 169. The member 163 is connected to a rod 170 that extends through a cylinder 171, and a piston 172 is fixed to rod 170 for operation within cylinder 171.

Fluid, preferably liquid, under pressure is adapted selectively to be delivered to opposite ends of cylinders 165 and 171 for moving the tool-head 160 along ways 162, and for moving the member 163 along ways 167, 168. In the present embodiment of the invention, the head 160 is adapted to be moved along either path at a relatively rapid traverse rate and at any one of a plurality of relatively slow feed rates. A source of low pressure liquid is provided for the rapid traverse of the head 160, and a feed-pressure pump, adapted to be supplied from the low pressure source, is adapted to be adjusted to deliver predetermined volumes of liquid at a relatively high pressure for feeding head 160.

A plurality of selectively operable valves are provided for controlling the admission of the pressure liquid to, and exhaust from the cylinders 165 and 171 in a liquid-locked system. Valves 173, 174 control the admission of high-pressure liquid to, and exhaust from opposite ends of cylinder 165; while valves 175, 176 control the admission of low-pressure liquid to, and

exhaust from opposite ends of the same cylinder. Valves 177, 178 control the admission of high-pressure liquid to, and the exhaust from opposite ends of cylinder 171; while valves 179, 180 control the admission of low pressure liquid to, and the exhaust from cylinder 171.

In order to prevent the head 160 from moving along either of its paths during periods of inactivity, and to prevent over-travel of the head due to momentum, clamping devices 181, 182 are applied to the extensions of each of the rods 164 and 170, respectively. The clamp 181 includes a slidable collar 183 in the form of a piston operating in a cylinder 184 that is adapted selectively to be supplied with liquid under pressure. A spring 185 on the side of piston 183 opposite that to which pressure liquid is applied normally causes said piston to urge a spring 183² into wedging engagement with a conical-recessed member 183' thereby effecting clamping of rod 164. A valve 186 is provided between the cylinder 184 and the valves 173, 174, 175 and 176 that is designed to admit liquid under pressure to cylinder 184 each time any one of said valves is operated. Valve 186 comprises a plurality of individual abutting piston elements 187, 188, 189 and 190 within a cylinder 191. The element 190 includes a head 192 adapted to control the admission of liquid under pressure to, and the exhaust from the cylinder 184. In a like manner, a valve 193, including piston elements 194, 195, 196 and 197, is provided between the clamp 182 and valves 177, 178, 179 and 180.

As previously stated, a liquid-locked system is employed, namely, one in which liquid is maintained at all times throughout the system, and which transmits pressure to any selected part of the system instantly upon actuating the correct valve. The system comprises a pump 198 adapted to deliver relatively high pressure liquid to effect release of clamps 181 and 182; to continuously urge all valves toward a low position where the apparatus remains inactive; and to actuate the traverse valves through a time-delay device, to be described later. The system also includes a pump 199 adapted to deliver liquid under a relatively low pressure, but great enough to effect traverse movement of head 160 along its intersecting paths of movement. The apparatus includes numerous conduits and ports for operatively connecting valves 173—180 to cylinders 165 and 171, and the system is so designed that with all of said valves in their low position, equal pressure is supplied to opposite sides of pistons 166 and 172 from pump 199 which pressure is sufficient to move head 160 at traverse speed. Accordingly, it is only necessary to exhaust the ends of cylinders 165, 171 in the direction it is desired to move head 160 to cause it to move at traverse speed.

A pump 200 is included in the system and is adapted to be supplied with liquid from pump 199 for delivering predetermined quantities of liquid under high pressure to selected sides of pistons 166, 172 for moving head 160 at feeding rates. The pump 200 is a commercial item that, per se, forms no part of this invention. It is similar to that disclosed in Patent 1,931,969 to Hans Thoma granted October 24, 1933. It comprises a portion 201 that is normally urged toward a horizontal position, shown in solid lines, by a spring 202 that cooperates with a push rod 202'. In the solid line position, zero feed is provided. The member 201 is adapted to be moved to a plurality of positions at which liquid received from

5 pump 199 is delivered in predetermined quantities to the system per revolution of the pump 200. The amount of these predetermined quantities of liquid depends upon the angular adjustment of member 201, and they are supplied to the system independently of the pressure encountered in feeding the head 160 along either of its paths. A relief valve 200' is provided, of course, for safety reasons.

10 Although the principles of the invention are adapted to be applied with equal facility to any apparatus including one or more members adapted to be moved along one or more paths, it is shown as applied to apparatus for turning work. Accordingly, a work support W (Fig. 2) is located in cooperative position relatively to the tool head 160. Since the feeding of the tool head toward the work on table W should bear a definite relation to the rotation of said table, the means (not shown) that rotates table W is connected to a gear 203 on the driving shaft for pump 200. Therefore, the rate at which table W turns definitely controls the rate at which head 160 is fed during a turning operation.

25 The specific construction including the valves, pumps, passages, etc., can best be understood by successively operating each valve and tracing the flow of liquid through the system from a source S to the cylinders 165 and 171.

30 With all valves 173 to 180 in their lower positions, member 201 of pump 200 in its horizontal zero-feed position and pumps 198 and 199 operating, liquid under relatively low traverse pressure is forced from pump 199 through a line 204, containing a relief valve 204', thence through a line 205 to a dividing point 206. Liquid passes through line 207 to the bore of valve 176, thence through a duct 208 to the bore of valve 174, thence through a line 209 to the top of cylinder 165. Liquid under the same pressure passes through a line 210 from point 206 to the bore of valve 175, thence through a duct 211 to the bore of valve 173, thence through a line 212 to the bottom of cylinder 165, thereby balancing piston 166. Likewise, liquid under relatively low traverse pressure passes from line 204 through a line 213 to a point 214. Liquid passes from said point through a line 215 to the bore of valve 179, thence through a duct 216 into the bore of valve 171, thence through a line 217 to the right-hand side of cylinder 171. Additionally, liquid under the same pressure passes from point 214 through a line 218 to the bore of valve 180, thence through a duct 219 to the bore of valve 178, thence through a line 220 to the left-hand side of cylinder 171, thereby balancing piston 172.

60 Movement of valve 173 to its upper position permits liquid to pass from pump 199 upwardly through line 204, thence through a line 221 to pump 200 that is in a predetermined position other than that for zero-feed since valve 173 is a feed valve. Predetermined quantities of liquid per revolution of pump 200 are continuously delivered through a line 222, thence through a line 223 into the bore of valve 173, thence through line 212 to the bottom of cylinder 165 tending to force piston 166 and tool head 160 upwardly. The continuous supply of these predetermined quantities of liquid per revolution of pump 200 is independent of the pressure encountered in moving head 160, however, above a safe limit of say 1000 pounds per square inch, pressure valve 200' opens. Liquid above piston 166 passes outwardly through line 209 into the bore of valve 174, thence through

line 208 to the bore of valve 176, thence through lines 207 and 205 to line 221 that leads to the intake side of pump 200. The pressure of the liquid above the piston 166 cannot exceed the relatively low traverse pressure because of the relief valve 204'. However, this traverse pressure against which feeding must act steadies the feed, preventing the tool from jumping ahead during interrupted cuts, etc. The construction provides a liquid locked system which requires only that amount of liquid from pump 199 that leaks out of the system—pump 199 merely maintaining a minimum traverse pressure throughout the system when no feeding is being performed.

Simultaneously with the flow of pressure liquid as described with valve 173 in its upper position, high pressure liquid is pumped from source S by pump 198 through a line 224, thence through a line 225 to chambers 226, 227 above valves 173, 174 for normally urging them to their lower position. A branch 228 leads from line 225 through which the high pressure liquid passes to a line 229 thence into a groove 230 surrounding a portion of valve 176 (to be described later) thence through a line 231 to a chamber 232 between plunger 190 and head 192 thereby forcing plungers 187—190 to the right. Additionally, the pressure liquid passes downwardly from line 231 through a line 233 into a valve chamber 234 for valve 176, thence through a duct 235 into a groove 236 surrounding the bore of valve 176, thence through a duct 237 into a groove 238 surrounding the bore of valve 174, thence through a duct 239 into the bore of valve 173. Since valve 173 is in its upper position, liquid under pressure flows out of the bore of valve 173 through a line 240 into the bore of valve 186 between plungers 187 and 188. Since the effective area of the right-hand face of plunger 188 is greater than that of the left-hand face of plunger 190, plungers 188, 189 and 190 move leftward, whereupon head 192 opens chamber 232 to a line 241 through which pressure liquid passes to clamp 181 causing collet 183' to move upwardly against the action of spring 185 thereby releasing rod 164. Accordingly, head 160 moves upwardly until the force that holds valve 173 in its upper position is released, whereupon the high pressure liquid in chamber 226 forces valve 173 downwardly thereby closing off the line 223 to line 212 and establishing a balanced traverse pressure on both sides of piston 166. When valve 173 moves to its lower position, it also cuts off communication between duct 239 and line 240 and opens an exhaust port 242. When this occurs, the pressure in chamber 232 forces plungers 187 to 190 rightward cutting off communication between lines 231 and 241, exhausting line 241 to the atmosphere through a port 243 and forcing the liquid between plungers 187 and 188 back through line 240 into the bore of valve 178, thence through the exhaust port 242 and an exhaust line 244 to the source S. Opening of port 243 permits spring 185 to render clamp 181 effective to prevent further movement of head 160.

Upon movement of valve 174 to its upper position with member 201 in the same or a different feeding position, predetermined quantities of liquid under pressure per revolution of the rotor of pump 200 pass through lines 222 and 223 into a groove 245 surrounding the bore of valve 173, thence through a duct 246 into the bore of valve 174, thence through the line 209 to the top of cylinder 165. Liquid below piston 166 passes through line 212 into the bore of valve 173, thence through line 211 to the bore of valve 175, thence

through lines 210 and 205 into line 221 ahead of pump 199. Any pressure in excess of the traverse pressure is relieved through valve 204'.

While valve 174 is in its upper position, high-pressure liquid from chamber 234 passes through duct 235, groove 236 and duct 237 into the bore of valve 174, thence through a line 247 to the bore of valve 186 between plungers 188 and 189 forcing plungers 189 and 190 to the left thereby admitting liquid under pressure from chamber 232 to line 241 whereby clamp 181 is released.

Upon release of the force holding valve 174 in its upper position, high-pressure liquid in chamber 227 forces said valve downwardly cutting off communication between ducts 247, 237 and lines 209, 246, respectively, and opening an exhaust port 248. Accordingly, no additional liquid is pumped by pump 200 through line 209 to the top of cylinder 165, and low traverse pressure is established on each side of piston 166. Plungers 189 and 190 are moved rightward by the pressure liquid in chamber 232, thereby rendering clamp 181 effective.

The traverse movement of head 160 usually occurs immediately following a feeding movement. In order to provide ample time within which the tool 161 cleans up the work when a feeding cut is terminated, a time-delay is provided that is effective to prevent the beginning of a traverse movement of head 160 for a predetermined short time interval after valves 175, 176, 179 and 180 are actuated.

Valve 175 includes a mechanically-operated plunger 249. This plunger comprises an upper head portion 250 having an effective area less than the upper face area of a lower portion 251. High-pressure liquid from line 228 passes through a line 252, thence into a groove 253 that encircles a portion of valve 175, thence through a line 254 to the bore of plunger 249, and forces plunger 251 downwardly. Additionally, said high pressure liquid enters an annular chamber 256 surrounding a piston 257 and acts on a flange 258 thereof forcing said piston downwardly until a flange 259 thereof engages a stop 260. Furthermore, high pressure liquid from the bore 255 passes through a duct 261 into the bore of valve 175, acts against a fixed plate 262 and valve 175 forcing the latter to a low position.

Adjustable means, to be described later, is provided for moving valve 249 upwardly a predetermined distance whereby the lower face of head 250 uncovers a port 263 a pre-determined amount. Liquid under high pressure from chamber 255 passes through port 263 into the cylinder containing piston 257, and acts against its lower face and a fixed plate 264. Simultaneously therewith, liquid passes from port 263 to the bore of valve 175 above plate 262. Since the lower face area of piston 257 is substantially greater than that of the lower face of the top spool of valve 175, piston 257 rises until flange 258 engages stop 260. Thereafter, valve 175 rises to the limit of its stroke. The amount port 263 is opened will determine the flow of liquid under pressure into the cylinder containing piston 257, the rate of upward movement of said piston and hence the time-delay or dwell before initiating the upward movement of valve 175.

As previously stated, when all valves 173 to 180 are in their lower position, relatively low traverse pressure is maintained on both sides of pistons 166 and 172. When valve 175 moves to its upper limit, it cuts off an exhaust 265 and permits liquid to flow from chamber 255 through a duct 266 into the bore for valve 175, thence through a line 267

into the bore of valve 186 between plunger 187 and the end of said valve bore, forcing elements 187 to 190 leftward thereby admitting liquid under pressure to line 241 and effecting release of clamp 181. Additionally, when valve 175 moves upwardly, it establishes communication between line 211 and an exhaust port 268 in the bore for valve 175. Accordingly, liquid in the lower end of cylinder 165 passes outwardly through line 212 into the bore for valve 173, thence through line 211 into the bore for valve 175, and finally through exhaust port 268.

Upon the release of the force holding plunger 249 in its upper position, the pressure liquid within chamber 255 acts on the top face of member 251, which face is greater in area than that of the lower face of valve head 250, consequently forcing valve plunger 249 downwardly cutting off port 263 from chamber 255 and opening it to an exhaust 269. Accordingly, the pressure liquid holding plunger 257 and valve 175 in their upper positions exhausts through port 269 and the pressure liquid in annular chamber 256 and that which passes through duct 261 forces piston 251 and valve 175 to their lower positions.

As valve 175 moves to its lower position, exhaust port 265 is opened and communication between duct 266 and line 267 is cut off thereby rendering clamp 181 effective. At the same time, exhaust port 268 is closed and communication between lines 210 and 211 is re-established thereby balancing the traverse pressure on each side of piston 186.

The valve 178 and its time-delay is identical with that of valve 175 and its time-delay. Movement of a plunger 270 upwardly a pre-determined distance by means similar to that for raising plunger 249 admits liquid under pressure from chamber 234 to a cylinder 271 containing a piston 272. Pressure liquid also flows into the space between the bottom face of the top spool of valve 176 and a fixed plate 273. Accordingly, piston 272 moves upwardly to the top of its stroke before valve 176 is raised throughout the limit of its stroke.

Upward movement of valve 176 cuts off an exhaust port 274 and establishes communication between duct 235 and a line 275, through which pressure liquid passes to valve 186 between plungers 189 and 190, forcing plunger 190 leftward thereby admitting pressure liquid to line 241 and releasing clamp 181. At the same time, an exhaust port 276 of the bore for valve 176 is opened and liquid from the top of cylinder 165 passes outwardly through line 209 into the bore of valve 174, thence through duct 208 to the bore of valve 176 and thence through the exhaust port 276. Upon release of the force holding plunger 270 in its upper position, it moves downwardly thereby permitting the pressure liquid that holds piston 272 and valve 176 in their upper positions to exhaust through a port 277, whereupon said piston and valve descend to their lower positions due to the pressure liquid in chamber 234. As valve 176 descends it opens exhaust port 274 to line 275 and cuts off communication between duct 235 and line 275, whereupon clamp 181 becomes effective. At the same time, exhaust port 276 is closed and communication is re-established between line 207 and duct 208 thereby balancing the traverse pressure on each side of piston 186.

The operation and function of valves 177, 178, 179 and 180 are identical with that of valves 173, 174, 175 and 176, respectively. The feed-pressure 200 is common to both sets of valves and dis-

tributes predetermined quantities of liquid under high pressure to selected sides of both pistons 166 and 172 depending upon which valve 173, 174, 177 or 178 is operated. Additionally, valves 178 and 180 include time-delay means identical with that of valves 175 and 176. Furthermore, valve 193 is identical in function and operation with that of valve 186. It controls clamp 182 and is governed by valves 177 to 180, inclusive.

With a predetermined angular setting of member 201 for a given feed, movement of valve 177 to its upper position will permit high-pressure liquid to pass from line 222 through a line 278 into the bore of valve 177, thence through the line 217 to the right-hand side of piston 172.

Liquid under pressure on the left-hand side of piston 172 passes outwardly through line 220 into the bore of valve 178, thence through a duct 218 to the bore of valve 180, thence through lines 218 and 213 to line 221 ahead of pump 199. At the same time, liquid under pressure is maintained by pump 198 in lines 224, 279, 280, 281, groove 282 surrounding a portion of valve 179, line 283 and chamber 284. Additionally, liquid under pressure is maintained in lines 285, a groove 286 surrounding a portion of valve 180, lines 287, 288, chamber 289, line 290 and chamber 291. Accordingly, as valve 177 moves to its upper position, high pressure liquid passes from chamber 289 through a duct 292 into a groove 293 surrounding valve 180, thence through a duct 294 into a groove 295 surrounding valve 178, thence through a duct 296 into the bore of valve 177, thence through a line 297 into the bore of valve 193 between plungers 194 and 195 thereby forcing plungers 195, 196 and 197 to the left, admitting liquid from chamber 291 to a line 298 and releasing clamp 182.

Upon release of the force holding valve 177 in its upper position, high-pressure liquid from line 279 passes into a chamber 299 forcing valve 177 downwardly. Downward movement of valve 177 interrupts communication between lines 278 and 217 and re-establishes communication between lines 216 and 217 thereby balancing the traverse pressure on each side of piston 172. At the same time, downward movement of valve 177 opens line 297 to an exhaust 300. Consequently, the pressure in chamber 291 forces plungers 195, 196 and 197 rightward thereby exhausting line 298 and rendering clamp 182 effective.

Movement of valve 178 to its upper position permits liquid under high pressure to pass from line 278 into a groove 301 surrounding the bore of valve 177, thence through a duct 302 into the bore of valve 178, thence through line 220 to the left-hand side of cylinder 171. Liquid from the right-hand side of piston 172 passes outwardly through line 217 into the bore for valve 177, thence through duct 216 to the bore for valve 178, thence through lines 215, 213 to line 221 ahead of pump 199. Additionally, with valve 178 in its upper position, high-pressure liquid from chamber 289 passes through ducts 292 and 294 into the bore of valve 178, thence through a line 303 to the bore of valve 193 between plungers 195, 196 thereby forcing plungers 196 and 197 leftward, admitting pressure liquid to line 298 and releasing clamp 182. Upon release of the force holding valve 178 in its upper position, high-pressure liquid from line 279 enters a chamber 304 forcing said valve downwardly. Downward movement of valve 178 interrupts communication between duct 302 and line 220. It also re-establishes communication between line 220 and duct 219 thereby balancing the traverse pres-

sure on each side of piston 172. Additionally, as valve 178 moves downwardly, it interrupts communication between duct 294 and line 303. It also opens line 303 to an exhaust 305, whereupon plungers 196 and 197 move rightward, venting line 298 to the atmosphere and rendering clamp 182 effective.

Movement of a member 306 upwardly a predetermined distance by means to be described later passes liquid under pressure at a determined rate through a port 307 into cylinders containing a piston 308 and the top spool of valve 179 causing the piston 308 to rise to its upper limit and then valve 179 to rise. As valve 179 rises, it establishes communication between duct 216 and an exhaust port 309, and interrupts communication between duct 216 and line 215, whereupon liquid on the right-hand side of piston 172 passes through line 217 to the bore of valve 177, thence through duct 216 to the bore of valve 179 thence to the atmosphere through exhaust port 309. At the same time valve 179 cuts off an exhaust port 310 and permits pressure liquid from chamber 284 to pass through a duct 311 into the bore of valve 179, thence through a line 312 to the bore of valve 193 moving piston members 194 to 197 leftward, admitting pressure liquid to line 298 and releasing clamp 182. Upon release of the force holding member 306 in its upper position, it descends thereby permitting the liquid beneath piston 308 and that beneath the top spool of valve 179 to pass through port 307 to an exhaust port 313, whereupon piston 308 and valve 179 descend. As valve 179 descends, exhaust port 309 is closed and communication is re-established between line 215 and duct 216 thereby balancing the traverse pressure on both sides of piston 172. At the same time duct 311 is cut off from line 312, which latter is then open to exhaust port 310 whereupon plungers 194 to 197 move rightward exhausting line 298 and rendering clamp 182 effective.

Finally, movement of a plunger 314 to a predetermined upper position, permits liquid from chamber 289 to pass through a duct 315 into a cylinder beneath a piston 316 and beneath the top spool of valve 180 causing the piston to rise at a predetermined rate and thereafter the valve 180. Upward movement of valve 180 interrupts communication between line 218 and duct 219. It also vents duct 219 to an exhaust port 317, whereupon liquid on the left-hand side of piston 172 passes outwardly through line 220 into the bore of valve 178, thence through duct 219 to the bore of valve 180, thence to the atmosphere through the exhaust port 317. Additionally, when valve 180 is in its upper position, pressure liquid from chamber 289 passes through duct 292 to the bore of valve 180, thence through a line 318 to the bore for valve 193 forcing piston 197 leftward, admitting liquid to line 298 and releasing clamp 182.

Upon release of the force holding plunger 314 in an upper position, it descends permitting the liquid beneath piston 316 and beneath the top spool of valve 180 to pass outwardly through duct 315 to an exhaust port 319, whereupon said piston and valve 180 descend due to the pressure liquid from chamber 289 passing through lines 288, 287 and through a duct 320 that delivers said liquid into a chamber between a fixed plate 321 and one face of a spool of valve 180. As valve 180 descends, it closes exhaust 317 and reestablishes communication between line 218 and duct 219 thereby equalizing the traverse

pressure on both sides of piston 172. It also interrupts communication between duct 292 and line 318 and opens line 318 to and exhaust 322, whereupon piston 197 moves rightward, exhausting line 298 and rendering clamp 182 effective.

Selective actuation of valves 173 to 180 inclusive is adapted to be effected by the successive indexing of a pattern drum 323 from station to station about a horizontal axis. The drum 323 is provided with circumferentially arranged series of holes 324 beneath valves 173, 174, 177, 178 and plungers 251, 270, 306 and 314, as well as beneath the stem 202' which supports spring 202 of the feed-pressure pump 200. Dogs 325 are adapted to be fixed to said drum by means passing through holes 324. These dogs are adapted to be arranged on the drum in accordance with a predetermined pattern for controlling the movement of the head 160 to produce the desired pattern. Drum 323 is adapted to be preset by the operator each time it is desired to produce a different cycle of operation of head 160 in performing work. This pre-setting of drum 323 is to be distinguished from the designing of certain types of automatic machinery in which a pre-determined fixed cycle of operation is built into the machine. The operation of the apparatus in performing a relatively simple pattern will be described later.

Successive indexing of drum 323 is adapted to be effected by any desirable power-operated means. In the embodiment disclosed, a Geneva stop wheel 326 fixed to drum 323 is adapted to be actuated by a crank 327. Crank 327 is connected to a motor 328 that is provided with a cam disc 329. The disc 329 cooperates with a holding switch 330 such that upon energization of the circuit for motor 328, switch 330 will close and remain closed only for a single revolution of crank 327.

Energization of the circuit for motor 328 is adapted selectively to be effected in response to any position the head 160 may assume along its paths of motion. Accordingly, the source of power that is employed to index drum 323 is independent of the force required to move head 160, but is rendered effective by the motion of said head. The extension of rod 170, connected to head 160, is provided with a finger 331 that is adapted to move longitudinally over a drum 332. Drum 332 is provided with as many peripherally-spaced longitudinal slots 333 as there are holes 324 in a series surrounding drum 323. Dogs 334 are adapted to be adjustably positioned within selected slots 333 for cooperation with finger 331. Drum 332 is adapted to be mounted for slight axial movement on either side of a neutral position, to which position it is normally urged. The resilient mounting for drum 332 comprises a cylinder 335 containing a spring 336. Discs 337, 338 are located within said cylinder at opposite ends of spring 336, and a rod 339 extends through the entire assembly. Rod 339 is provided with a nut 340 and a shoulder 341 at opposite ends of a reduced portion 342. The discs 337, 338 abut against nut 340 and shoulder 341 and movement of rod 339 is, therefore, permitted in either direction from a neutral position. However, upon release of the force that moves rod 339 in either direction, it is instantly returned to its neutral position. Rod 339 is connected to drum 332 through a link 343 that fits within a circumferential groove 344 on a shaft 345 that supports said drum.

Shaft 345 is provided with an additional groove

346 within which rests a button 347 of a normally-open switch 348. The switch 348 is in circuit with motor 328. Accordingly, slight axial movement of drum 332 in either direction closes switch 348 and energizes the circuit for motor 328. Shaft 345 is provided with a gear 350. Gear 350 meshes with a gear 351 fixed to rotate with drum 323. Accordingly, upon head 160 moving along its horizontal path due to a setting on drum 323, finger 331 will engage a dog 334 in a slot 333 of drum 332 and move said drum axially a slight amount whereupon switch 348 closes causing motor 328 to index drum 323 to its next succeeding station where the same or a different set of valves 173-180 is actuated. Slight axial movement between gears 350 and 351 may occur without dis-engaging said gear. Simultaneously with the indexing of drum 323, drum 332 is also indexed to position the next succeeding slot 333 in line with finger 331. This new slot may contain a dog 334 adapted to be engaged by finger 331 thereby determining the amount of movement of head 160 for the new setting on drum 323.

Rod 164 is likewise provided with a finger 352 adapted to engage dogs 353 on a drum 354. Drum 354 is mounted for slight axial movement in the same manner that drum 332 is mounted, and a switch 355, provided for drum 354, is connected in parallel with switch 348. Drum 354 is provided with a shaft 356 journaled in a bracket 357 integral with slide member 163. Accordingly, movement of head 160 horizontally moves drum 354 in the same direction to maintain it at all times in cooperative position relatively to finger 352. A bevel gear 358 keyed to shaft 356 meshes with a bevel gear 359 splined on a shaft 360 that is held against axial movement. Shaft 360 is provided with a gear 361, keyed thereto, which meshes with gear 351 of drum 323.

From the foregoing, it is evident that the fingers 331 and 352 move proportionally to the movement of head 160, and that upon engagement of either of said fingers with dogs 334 and 353, motor 328 is rendered active to index drum 323 to its next succeeding position. Also, upon the indexing of drum 323, both drums 332 and 354 are likewise indexed to position their next succeeding slots in cooperative position with fingers 331 and 352, respectively. Accordingly, an arrangement is provided whereby the movement of head 160 along its respective paths, as dictated by one setting on drum 323, is not affected by subsequent movements of head 160 due to the same or different settings on drum 323. This arrangement renders the apparatus extremely versatile and permits head 160 to perform a cycle of operation that is adapted to include a series of operations and wherein the path, rate, starting and stopping of movement of head 160 for each operation can be selected independently of the selection for every other operation.

As previously described, adjustable means is provided for varying the angular position of member 201 of feed-pressure pump 200 to provide varying feed rates. The means comprises dogs 325 of varying height that are adapted to be attached to drum 323 by means passing through the holes 324 in line with the stem 202 of member 201. Obviously, when it is desired to feed head 160 along either of its paths, it is only necessary to place a dog 325 at the proper place on drum 323 to move the desired feed valve 173, 174, 177 or 178 to its upper position, and to place a dog 325 of a height commensurate with

the desired feed on drum 323 in axial line with the mentioned feed dog and in radial alignment with stem 202.

Furthermore, adjustable means is also provided to move the traverse valve plungers 251, 270, 306, and 314 upwardly predetermined distances to control the opening of the port 263, and those for the cylinders containing pistons 272, 308 and 316. Accordingly, the flow of liquid into said cylinders may be controlled and hence the time-delay prior to beginning of traverse movement of head 160 may be varied at will. This means comprises varying height dogs 325 that are adapted selectively to be attached to drum 323 in line with valve plungers 251, 270, 306 and 314.

In order to better understand the principles of the invention, the apparatus disclosed is shown set up to perform a cycle of operation on a piece of material 364. The material to be worked is 20 cylindrical in form as shown by the dotted lines of Fig. 2. Assume that it is desired to produce a great number of stepped pieces of work from pieces of material such as 364. The form of the finished pieces is represented by solid lines in Fig. 2.

For initially setting up the machine, an auxiliary crank 365 is provided including a handle 366. The crank 365 is adapted to cooperate with the Geneva wheel 326 in the same manner that 30 crank 327 cooperates therewith.

With the pumps 198 and 199 operating, no dogs on any of the drums 323, 332, 354 and the tool 161 at a starting point spaced from the work, the apparatus is in condition for setting.

35 A dog 325 is secured to drum 323 at point I such that upon indexing the drum said dog will move plunger 306 upwardly. The distance between the starting point and point I (Fig. 2) is laid off from finger 331 and a dog 334 is secured 40 to drum 332 at point I in the slot 333 thereof that will align itself with finger 331 upon indexing drum 323. Switch 330 is manually closed for an instant, whereupon drum 323 is indexed. Accordingly, tool 161 is moved to point I (Fig. 2) 45 at which it stops due to finger 331 engaging dog I on drum 332 and moving said drum axially to close switch 348 to index drum 323. Hand crank 365 is turned in a direction to reversely index drum 323 through only one-half an index 50 such that number I dog thereon does not engage plunger 306. A dog 325 is secured to drum 323 at point II in line with valve 178 and such that upon a forward half index of drum 323, it will raise valve 178. A dog 325 is also secured to drum 323 in axial alignment with dog number II and beneath stem 202'. The height of this dog 55 325 depends upon the rate of feed desired between points I and II (Fig. 2) for establishing the diameter (a) of the work 364. The distance between points I and II (Fig. 2) is laid off along drum 332 from finger 331, and a dog 334 is secured to said drum at point II thereon in the slot 333 thereof that will align itself with finger 331 upon a forward half index of drum 323. 60 Handcrank 365 is then turned to give a forward half index to drum 323, whereupon tool 161 moves to point II (Fig. 2) and stops.

Handcrank 365 is again turned to give a reverse half index, and a dog 325 is secured to drum 323 at point III such that upon a forward half index of drum 323 it will raise plunger 251. The vertical distance between points II and III Fig. 2 is laid off from finger 352 and a dog 353 is secured to drum 354 at point III in the slot 353' thereof that will align itself with finger 352 upon

a forward half index of drum 323. Handcrank 365 is then turned to provide a forward half index of drum 323, whereupon tool 161 moves from point II to III Fig. 2 at traverse speed at which point it stops.

Drum 323 is again given a reverse half index by hand, and a dog 325 is secured to drum 323 at point IV, and a dog 325 of the desired height is secured in axial alignment with number IV dog and in radial alignment with stem 202'. The distance between points III and IV Fig. 2 is laid off from finger 352 and a dog 353 is secured to drum 354 at point IV in the slot 353' thereof that will align itself with finger 353 upon a forward half index of drum 323. Drum 323 is given a forward half index whereupon tool 161 moves from point III to point IV (Fig. 2) at which it stops. Drum 323 is given a reverse half index and a dog 325 is secured thereto at point V. The height of dog 325 at point V depends upon the dwell desired at the point IV (Fig. 2). The distance between points IV and V is laid off from finger 352 and a dog 353 is secured to drum 354 at point V within the slot 353' that aligns itself with finger 352 upon a forward half index of drum 323. Drum 323 is then given a forward half index, whereupon tool 161 moves from point IV to point V Fig. 2 where it stops.

The above procedure is followed in setting dogs at points V to XII inclusive on drum 323 with corresponding dogs on the correct drum 332 or 354. Additionally, the correct size of dogs 325 are secured at the proper points on drum 323 to control the feed rate and time of dwell, for traverse, respectively.

When the apparatus is completely set up so that it has passed through its entire cycle, the set-up work piece is measured for accuracy and any errors therein are compensated for by re-adjustment of the dogs 334 and 353 on drums 332 and 354.

Upon completion of the set-up and error-compensating re-adjustment, if any is required, it is only necessary to load the support W, push a button to close switch 330 to initiate the cycle and remove the completed work piece each time the apparatus comes to rest.

As previously stated, the subject matter of this application is similar to that of application Serial #353,935 filed August 23, 1940. Accordingly, a plurality of heads or members such as 160 may be provided with substantially identical fluid-operated apparatuses and controls therefor, the operation of which controls may be initiated from the drum 323 in the same manner as the operation of the plurality of controls of said application 353,935 are initiated from the drum 102 of said application.

Referring to Fig. 3, an electrical circuit is disclosed for three appliances similar to that of Fig. 1 arranged in cooperative relation. As shown, the motors 328, 328₁ and 328₂ are adapted to index control drums 323, 323₁ and 323₂, respectively. Each of the circuits includes five switches in parallel for starting the motors 328, 328₁ and 328₂. The circuit includes switches 348, 348₁ and 348₂; 355, 355₁, 355₂; and 330, 330₁, 330₂; arranged in the manner described with respect to the switches 348, 355 and 330 of the appliance of Fig. 1. Additionally, the drum 323 contains means for closing switches 367 and 368 in the circuits for motors 328₁ and 328₂, respectively; drum 323₁ contains similar means for closing switches 367₁ and 368₁ in the circuits for motors 328 and 328₁, respectively; and drum 323₂ con-

tains similar means for closing switches 367₂ and 368₂ in the circuits for motors 328 and 328₁, respectively.

From the foregoing description of Figs. 1 and 3, it is evident that a plurality of separate members is adapted repeatedly to perform various cycles of operation in each of which may be produced selectively a plurality of different directions and rates of motion of the members 160 in accordance with the setting of the dogs on the individual drums 323; that at any time during operation of one unit, the operation of another unit may be started; and that the units may be operated individually or simultaneously such that numerous functions may be performed by numerous members in accordance with any predetermined sequential order.

Although the various features of the invention have been shown and described in detail to fully disclose one embodiment of the invention, it will be evident that numerous changes may be made in such details, and certain features may be used without others, without departing from the principles of the invention.

What is claimed is:

1. Apparatus comprising in combination, a member adapted successively to be moved in either direction along a path at any one of a plurality of speeds; a fluid-motor for moving said member; separate means for each direction of motion of said member adapted selectively to be operated for controlling the admission of fluid to, and exhaust from said motor; pre-settable means adapted selectively to operate a plurality of means including selected of said control means; a source of power for operating said pre-settable means; and means for determining the extent of successive movements of said member comprising separate adjustable means for each successive movement and responsive thereto at any point along the path of travel of said member for determining when said source of power is to be rendered effective, whereby both limits of movement of said member along said path may be varied.

2. Apparatus comprising in combination, a member adapted successively to be moved more than twice along a path at any one of a plurality of speeds; a fluid-motor for moving said member; separate means for each direction of motion of said member adapted selectively to be operated for controlling the admission of fluid to, and exhaust from said motor; pre-settable means adapted selectively to operate a plurality of means including selected of said controlling means; a source of power for operating said pre-settable means; and separate means responsive to each successive movement of said member for operating an electric circuit to render effective said source of power.

3. Apparatus comprising in combination, a member adapted successively to be moved more than twice along a path at any one of a plurality of speeds within a cycle of operation; a fluid-motor for moving said member; separate means for each direction of motion of said member adapted selectively to be operated for controlling the admission of fluid to, and exhaust from said motor; means adapted to be pre-set for selectively operating one or more of a plurality of means including selected of said controlling means; means for indexing said pre-settable means from station to station; a source of power for indexing said pre-settable means; and separate means for determining the extent of each successive movement of said member within said

cycle of operation comprising adjustable means responsive to the movement of said member and effective at a plurality of points along its path of travel for determining when said source of power is to be rendered effective, whereby both limits of movement of said member along said path may be varied.

4. Apparatus comprising in combination, a member adapted to be moved in either direction along a path at any one of a plurality of speeds; a fluid motor for moving said member; means adapted selectively to be operated for controlling the admission of fluid to, and exhaust from said fluid motor; means adapted to be pre-set for selectively operating one or more of a plurality of means including selected of said controlling means; means for indexing said pre-settable means from station to station; a source of power for indexing said pre-settable means; means responsive to the movement of said member for determining when said source of power is to be rendered effective; and means for indexing said determining means simultaneously with the indexing of said pre-settable means.

5. Apparatus comprising in combination, a member adapted to be moved in either direction along a path at any one of a plurality of speeds; a fluid motor for moving said member; means adapted selectively to be operated for controlling the admission of fluid to, and exhaust from said motor; pre-settable means adapted selectively to be indexed from station to station for operating one or more of a plurality of means including selected of said controlling means; a source of power for indexing said pre-settable means; and means adapted to be moved in response to the movement of said member to render said source of power effective, said last mentioned means being adapted to be indexed simultaneously with the indexing of said pre-settable means.

6. Apparatus comprising in combination, a member adapted to be moved in either direction along a path at any one of a plurality of speeds; a fluid motor for moving said member; a traverse-pressure pump adapted to maintain a balanced pressure on each side of said fluid motor during periods of inactivity; a feed-pressure pump adapted to be supplied with fluid from said traverse-pressure pump and adapted to be adjusted for delivering predetermined quantities of fluid to selected sides of said fluid motor independently of the pressure encountered in moving the piston of said motor; means adapted selectively to be operated for controlling the admission of fluid to, and exhaust from said fluid motor; means adapted to be pre-set for selectively operating one or more of a plurality of means including selected of said control means; a source of power for operating said pre-settable means; and means responsive to the movement of said member for determining when said source of power is to be rendered effective.

7. Apparatus comprising in combination, a member adapted to be moved in either direction along a path at any one of a plurality of speeds; a fluid motor for moving said member; a traverse-pressure pump adapted to maintain a balanced pressure on each side of said fluid motor during periods of inactivity; a feed-pressure pump adapted to be supplied with fluid from said traverse-pressure pump and adapted to be adjusted for delivering predetermined quantities of fluid to selected sides of said fluid motor independently of the pressure encountered in moving the piston of said motor; control means

adapted upon selective operation to exhaust fluid from selected sides of said fluid motor, to select the side of said motor to which said pre-determined quantities of fluid are adapted to be delivered and to connect the side of said motor, opposite that to which said fluid is delivered, to the inlet of said feed-pressure pump ahead of said traverse-pressure pump; means adapted to be pre-set for selectively operating one or more of a plurality of means including selected of said control means; a source of power for operating said control means; and means responsive to the movement of said member for determining when said source of power is to be rendered effective.

8. Apparatus comprising in combination, a member adapted to be moved in either direction along a plurality of paths at a plurality of speeds; separate fluid motors adapted to move said member along its respective paths at any one of said plurality of speeds; common means adapted to be pre-set for rendering effective one or more of a plurality of means including any one of said fluid motors; a source of power for operating said common means; and separate means for each path along which said member is adapted to be moved including adjustable means adapted to be located at the same or different points relatively to said path for determining when said source of power is to be rendered effective, during successive movements of said member along said path in a cycle of operation.

9. Apparatus comprising in combination, a member adapted to be moved in either direction along a plurality of paths at a plurality of speeds; separate fluid motors adapted to move said member along its respective paths at any of said plurality of speeds; common means adapted to be pre-set for rendering effective one or more of a plurality of means including any one of said fluid motors; a source of power for operating said common means; and separate means for each path along which said member is adapted to be moved for operating an electric circuit to render effective said source of power.

10. Apparatus comprising in combination a member adapted to be moved in either direction along a plurality of paths at a plurality of speeds; separate fluid motors adapted to move said member along its respective paths at any of said plurality of speeds; common means adapted to be pre-set and adapted to be indexed from station to station for rendering effective one or more of a plurality of means including any one of said fluid motors; a source of power for indexing said common means; and separate means for each path along which said member is adapted to be moved including adjustable means adapted to be located at the same or different points relatively to said path for determining when said source of power is to be rendered effective, during successive movements of said member along said path in a cycle of operation.

11. Apparatus comprising in combination, a member adapted to be moved in either direction along a plurality of paths at a plurality of speeds; separate fluid motors adapted to move said member along its respective paths at any of said plurality of speeds; common means adapted to be pre-set and adapted to be indexed from station to station for rendering effective one or more of a plurality of means including any one of said fluid motors; a source of power for indexing said common means; separate means for each path along which said member is adapted to be moved for determining when said source of power is to

be rendered effective; and means for indexing said separate means simultaneously with the indexing of said common means.

12. Apparatus comprising in combination a member adapted to be moved in either direction along a plurality of paths at a plurality of speeds; separate fluid motors adapted to move said member along its respective paths at any of said plurality of speeds; common means adapted to be pre-set and adapted to be indexed from station to station for rendering effective one or more of a plurality of means including any one of said fluid motors; a source of power for indexing said common means; separate means for each path along which said member is adapted to be moved and movable in response to the movement of said member for determining when said source of power is to be rendered effective; and means for indexing said separate means simultaneously with the indexing of said common means.

13. Apparatus comprising in combination, a member adapted to be moved in either direction along a plurality of paths at a plurality of speeds; separate fluid motors adapted to move said member along its respective paths at any of said plurality of speeds; a traverse-pressure pump adapted to maintain a balanced pressure on each side of said fluid motors during periods of inactivity; a feed-pressure pump adapted to be supplied with fluid from said traverse-pressure pump and adapted to be adjusted for delivering pre-determined quantities of fluid to selected sides of said fluid motors independently of the pressure encountered in moving the pistons of said motors; means adapted selectively to be operated for controlling the admission of fluid to, and exhaust from said fluid motors; common means adapted to be pre-set for operating selected of said controlling means; a source of power for operating said common means; and separate means for each path along which said member is adapted to be moved for determining when said source of power is to be rendered effective.

14. Apparatus comprising in combination, a member adapted to be moved in either direction along a plurality of paths at a plurality of speeds; separate fluid motors adapted to move said member along its respective paths at any of said plurality of speeds; a traverse-pressure pump adapted to maintain a balanced pressure on each side of said fluid motors during periods of inactivity; a feed-pressure pump adapted to be supplied with fluid from said traverse-pressure pump and adapted to be adjusted for delivering pre-determined quantities of fluid to selected sides of any one of said fluid motors independently of the pressure encountered in moving the piston of said motor; control means adapted upon selective operation to exhaust fluid from selected sides of said fluid motor, to select the side of said motor to which said pre-determined quantities of fluid are adapted to be delivered and to connect the side of said motor, opposite that to which said fluid is delivered, to the inlet of said feed-pressure pump ahead of said traverse-pressure pump; common means adapted to be pre-set for operating selected of said control means; a source of power for operating said common means; and separate means for each path along which said member is adapted to be moved for determining when said source of power is to be rendered effective.

15. Apparatus comprising in combination, a member; a support; a fluid motor for providing

more than two successive relative movements between said member and support within a cycle of operation; separate means for each direction of said relative movement for controlling the admission of fluid to, and the exhaust from said fluid motor; means adapted to be pre-set for operating selectively one or more of a plurality of means including selected of said controlling means; a source of power for operating said pre-settable means; and means for determining the extent of each relative movement within said cycle of operation comprising separate adjustable means responsive to each of said relative movements and effective at a plurality of points along the path of said relative movements for determining when said source of power is to be rendered effective, whereby both limits of said relative movement between said member and support may be varied.

16. Apparatus comprising in combination, a member; a support; a fluid motor for providing more than two successive relative movements between said member and support within a cycle of operation; separate means for each direction of said relative movement for controlling the admission of fluid to, and the exhaust from said fluid motor; means adapted to be pre-set for operating selectively one or more of a plurality of means including selected of said controlling means; a source of power for operating said pre-settable means; and means for determining the extent of each relative movement within said cycle of operation comprising separate adjustable means responsive to each of said relative movements and effective at a plurality of points along the path of said relative movements for operating an electric circuit to render effective said source of power.

17. Apparatus comprising in combination, a member; a support; a fluid motor for providing relative movement between said member and support; means for controlling the admission of fluid to, and the exhaust from said fluid motor; pre-settable means adapted to be indexed from station to station for operating selectively one or more of a plurality of means including selected of said controlling means; a source of power for indexing said pre-settable means; and means adapted to be indexed from station to station simultaneously with the indexing of said pre-settable means and responsive to said relative movement for determining when said source of power is to be rendered effective.

18. Apparatus comprising in combination, a member; a support; means for providing relative rotation between said member and support; a fluid motor for providing more than two successive relative rectilinear movements between said member and support during a cycle of operation; separate means for each direction of said relative rectilinear movement adapted selectively to be operated for controlling the admission of fluid to, and exhaust from said fluid motor; means adapted to be pre-set for operating selected of said controlling means; a source of power for operating said pre-settable means; and means for determining the extent of each of said relative rectilinear movements within said cycle of operation comprising separate adjustable means responsive to each of said relative rectilinear movements and effective at a plurality of points along the path of said relative rectilinear movements for determining when said source of power is to be rendered effective, whereby both limits of said

relative rectilinear movement between said member and support may be varied.

19. Apparatus comprising in combination, a member; a support; means for providing relative rotation between said member and support; a fluid motor for providing more than two successive relative rectilinear movements between said member and support during a cycle of operation; separate means for each direction of said relative rectilinear movement adapted selectively to be operated for controlling the admission of fluid to, and exhaust from said fluid motor; means adapted to be pre-set for operating selected of said controlling means; a source of power for operating said pre-settable means; and separate adjustable means responsive to each relative rectilinear movement within said cycle of operation for operating an electric circuit to render effective said source of power.

20. Apparatus comprising in combination, a member; a support; means for rotating said support; a fluid motor for providing more than two successive relative rectilinear movements between said member and said support during a cycle of operation; separate means for each direction of said relative rectilinear movement adapted selectively to be operated for controlling the admission of fluid to, and exhaust from said fluid motor; means adapted to be pre-set for moving selected of said controlling means; an additional source of power, separate from the power developed by the relative rectilinear motion between said member and support for operating said pre-settable means; and means for determining the extent of each of said relative rectilinear movements within said cycle of operation comprising separate adjustable means for each of said relative rectilinear movements responsive thereto and effective at a plurality of points along the path of said relative rectilinear movements for determining when said additional source of power is to be rendered effective whereby both limits of said relative rectilinear movement between said member and support may be varied.

21. Apparatus comprising in combination, a member; a support; means for providing relative rotation between said member and support; a fluid motor for providing relative rectilinear movement between said member and support; a traverse-pressure pump adapted to maintain a balanced pressure on each side of said fluid motor during periods of inactivity; a feed-pressure pump adapted to be supplied with fluid from said traverse-pressure pump and adapted to be adjusted for delivering pre-determining quantities of fluid to selected sides of said fluid motor independently of the pressure encountered in moving the piston of said motor; means adapted selectively to be operated for controlling the admission of fluid to, and exhaust from said fluid motor; means adapted to be pre-set for moving selected of said controlling means; a source of power for operating said pre-settable means; and means responsive to said relative rectilinear movement for determining when said source of power is to be rendered effective.

22. Apparatus comprising in combination, a member; a support; means for providing relative rotation between said member and support; a fluid motor for providing relative rectilinear movement between said member and support; a traverse-pressure pump adapted to maintain a balanced pressure on each side of said fluid motor during periods of inactivity; a feed-pressure pump adapted to be supplied with fluid from said trav-

erse-pressure pump and adapted to be adjusted for delivering pre-determined quantities of fluid to selected sides of said fluid motor independently of the pressure encountered in moving the piston of said motor; means adapted upon selective operation to exhaust fluid from selected sides of said fluid motor, to select the side of said motor to which said predetermined quantities of fluid are adapted to be delivered and to connect the 10 side of said motor, opposite that to which said fluid is delivered, to the inlet of said feed-pressure pump ahead of said traverse-pressure pump; means adapted to be pre-set for operating selected of said selectively-operable means; a source of power for operating said pre-settable means; and means responsive to said relative rectilinear movement for determining when said source of power is to be rendered effective.

23. Apparatus comprising in combination, a support; a member; fluid motors for providing relative movement between said member and support along a plurality of paths; means adapted to control the admission of fluid to, and exhaust from said fluid motors; common means adapted to be pre-set for operating selected of said controlling means; a source of power for operating said common means; and separate means for each path along which said relative movement is to be effected for determining when said source 30 of power is to be rendered effective.

24. Apparatus comprising in combination, a support; a member; fluid motors for providing relative movement between said member and support along a plurality of paths; means adapted to control the admission of fluid to, and exhaust from said fluid motors; common means adapted to be pre-set for operating selected of said controlling means; a source of power for operating said common means; and separate means for each 35 path along which said relative movement is to be effected and responsive to said relative movement for operating an electric circuit to render effective said source of power.

25. Apparatus comprising in combination, a support; a member; fluid motors for providing relative movement between said member and support along a plurality of paths; means adapted to control the admission of fluid to, and exhaust from said fluid motors; common means adapted to be pre-set for operating selected of said controlling means; a source of power for indexing said common means from station to station; separate means for each path along which said relative movement is to be effected for determining when said source of power is to be rendered effective; and means for indexing said separate means from station to station simultaneously with the indexing of said common means.

26. Apparatus comprising in combination, a member; a support; means for providing relative rotation between said member and support; separate fluid motors for providing a plurality of relative rectilinear movements between said member and support along a plurality of paths at a plurality of speeds during a cycle of operation; common means adapted to be pre-set for rendering effective any of said fluid motors; a source of power for operating said common means; and separate means for each path of said relative rectilinear movement including separate adjustable means for each relative rectilinear movement of said member within said cycle of operation for determining when said source of power is to be rendered effective.

27. Apparatus comprising in combination, a

member; a support; means for providing relative rotation between said member and support; separate fluid motors for providing relative rectilinear movement between said member and support along a plurality of paths at a plurality of speeds; common means adapted to be pre-set for rendering effective any of said fluid motors; a source of power for operating said common means; and separate means for each path of, and responsive to said relative rectilinear movement for operating an electric circuit to render effective said source of power.

28. Apparatus comprising in combination, a member; a support; means for rotating said support; separate fluid motors for providing relative rectilinear movement between said member and support along a plurality of paths at a plurality of speeds; common means adapted to be pre-set for rendering effective any of said fluid motors; an additional source of power, separate from that developed by the relative rectilinear motion between said member and support, for operating said common means; and separate means for each path of, and responsive to said relative rectilinear movement for determining when said additional source of power is to be rendered effective.

29. Apparatus comprising in combination, a member; a support; means for providing relative rotation between said member and support; separate fluid motors for providing relative rectilinear movement between said member and support along a plurality of paths at a plurality of speeds; a traverse-pressure pump adapted to maintain a balanced pressure on each side of said fluid motors during periods of inactivity; a feed-pressure pump adapted to be supplied with fluid from said traverse-pressure pump and adapted to be adjusted for delivering pre-determined quantities of fluid to selected sides of said fluid motors independently of the pressure encountered in moving the pistons of said motors; means for controlling the admission of fluid to, and exhaust from said fluid motors; common means adapted to be pre-set for rendering effective any of said control means; a source of power for operating said common means; and separate means for each path of, and responsive to said relative rectilinear movement for determining when said source of power is to be rendered effective.

30. Apparatus comprising in combination, a member; a support; means for providing relative rotation between said member and support; separate fluid motors for providing relative rectilinear movements between said member and support along a plurality of paths at a plurality of speeds; a traverse-pressure pump adapted to maintain a balanced pressure on each side of said fluid motors during periods of inactivity; a feed pressure pump adapted to be supplied with fluid from said traverse pressure pump and adapted to be adjusted for delivering predetermined quantities of fluid to selected sides of any one of said fluid motors independently of the pressure encountered in moving the piston of said motor; control means adapted upon selected operation to exhaust fluid from selected sides of said fluid motor, to select the side of said motor to which said pre-determined quantities of fluid are adapted to be delivered and to connect the side of said motor, opposite that to which said fluid is delivered, to the inlet of said feed-pressure pump ahead of said traverse-pressure pump; common means adapted to be pre-set for operating any of said control means; a source of power for op-

erating said common means; and separate means for each path of, and responsive to said relative rectilinear movement for determining when said source of power is to be rendered effective.

5 31. Apparatus comprising in combination, a plurality of appliances, each including a member adapted to be moved in either direction at a plurality of speeds along a plurality of paths; a fluid motor connected to each of said members for each path along which it is adapted to be moved; means adapted selectively to be operated for controlling the admission of fluid to, and exhaust from selected sides of said fluid motors; pre-settable means associated with each appliance and common to its motors and adapted selectively to operate a plurality of means including means for controlling the pre-settable means associated with all other appliances and selected of its control means for the motors; a source of power for each appliance for operating its common means; and means responsive to the movement of the member of each appliance for determining when the source of power for its common means is to be rendered effective.

25 32. Apparatus comprising in combination, a plurality of appliances, each including a member adapted to be moved in either direction at a plurality of speeds along a path; a fluid motor connected to each of said members; means adapted selectively to be operated for controlling the admission of fluid to, and exhaust from selected sides of said fluid motors; pre-settable means associated with each appliance adapted selectively to operate a plurality of means including means for controlling the pre-settable means associated with all other appliances and selected of the control means for its motor; a source of power for each appliance for operating its pre-settable means; and means responsive to the movement of the member of each appliance for determining when the source of power for its pre-settable means is to be rendered effective.

45 33. In a fluid system, a fluid motor; a traverse-pressure pump adapted to maintain a balanced pressure on each side of said fluid motor during periods of inactivity; a feed-pressure pump adapted to be supplied with fluid from said traverse-pressure pump and adapted to be adjusted for delivering pre-determined quantities of fluid to selected sides of said fluid motor independently of the pressure encountered in moving the piston of said motor; and means adapted upon selective operation to exhaust fluid from selected sides of said fluid motor, to select the side of said motor to which said pre-determined quantities of fluid are adapted to be delivered and to connect the side of said motor, opposite that to which said fluid is delivered, to the inlet of said feed-pressure pump ahead of said traverse-pressure pump.

60 34. In a fluid system, a plurality of fluid motors; a traverse-pressure pump adapted to maintain a balanced pressure on each side of said fluid motors during periods of their inactivity; a feed-pressure pump adapted to be supplied with fluid from said traverse-pressure pump and adapted to be adjusted for delivering pre-determined quantities of fluid to selected sides of said fluid motors independently of the pressure encountered in moving the pistons of said motors; and means adapted upon selective operation to exhaust fluid from selected sides of said fluid motors, to select the sides of said motors to which said predetermined quantities of fluid are adapted to be delivered and to connect the sides of said motors, opposite those to which said fluid is delivered, to

the inlet of said feed-pressure pump ahead of said traverse-pressure pump.

35. Apparatus comprising in combination, a member; means for moving said member in either direction along a path at a plurality of feed rates and at a traverse rate; control means for rendering said member-moving means effective; means associated with said control means for providing a time delay immediately prior to the movement of said member at traverse rate; means adapted to be pre-set for selectively operating said control means; a source of power for operating said pre-settable means; and means responsive to the movement of said member for determining when said source of power is to be rendered effective.

36. Apparatus comprising in combination, a member; means for moving said member in either direction along a path at a plurality of feed rates and at a traverse rate; control means for rendering said member-moving means effective; means associated with said control means for providing a time delay of a pre-determined duration immediately prior to the movement of said member at traverse rate; means adapted to be pre-set for selectively operating said control means and for determining the duration of said time delay; a source of power for operating said pre-settable means; and means responsive to the movement of said member for determining when said source of power is to be rendered effective.

37. Apparatus comprising in combination, a member; a fluid motor connected to said member; means adapted selectively to be operated for controlling the admission of fluid to, and exhaust from said motor for moving said member in either direction along a path at a plurality of feed rates and at a traverse rate; means associated with said control means for providing a time delay of a pre-determined duration immediately prior to the movement of said member at traverse rate; means adapted to be pre-set for selectively operating said control means and for determining the duration of said time delay; a source of power for operating said pre-settable means; and means responsive to the movement of said member for determining when said source of power is to be rendered effective.

38. Apparatus comprising in combination, a member; means for moving said member in either direction along a plurality of paths at a plurality of feed rates and at a traverse rate; separate control means for each path along which said member is adapted to be moved for rendering said member-moving means effective; means associated with said control means for providing a time delay immediately prior to the movement of said member at traverse rate; common means adapted to be pre-set for selectively operating said control means; a source of power for operating said common means; and means responsive to the movement of said member for determining when said source of power is to be rendered effective.

39. Apparatus comprising in combination, a member; means for moving said member in either direction along a plurality of paths at a plurality of feed rates and at a traverse rate; separate control means for each path along which said member is adapted to be moved for rendering said member-moving means effective; means associated with said control means for providing a time delay of a pre-determined duration immediately prior to the movement of said member at traverse rate; common means adapted to be pre-set for selectively operating said control means and for determining the duration of said

time-delay; a source of power for operating said common means; and means responsive to the movement of said member for determining when said source of power is to be rendered effective.

40. Apparatus comprising in combination, a member adapted to be moved in either direction along a plurality of paths at a plurality of feed rates and at a traverse rate; separate fluid motors adapted to move said member along its respective paths at any of said rates; means adapted selectively to be operated for controlling the admission of fluid to, and exhaust from said motors; means associated with said control means for providing a time delay of a pre-determined duration immediately prior to the movement of said member at traverse rate; common means adapted to be pre-set for selectively operating said control means and for determining the duration of said time delay; a source of power for operating said common means; and means responsive to the movement of said member for determining when said source of power is to be rendered effective.

41. Apparatus comprising in combination, a member adapted to be moved in either direction along a path at any one of a plurality of speeds; a fluid-motor connected to said member; clamping means associated with said fluid motor and normally acting to prevent its movement; a plurality of means adapted selectively to be operated for controlling the admission of fluid to, and exhaust from selected sides of said fluid motor for moving said member in either direction; pre-settable means adapted upon movement to operate any of said control means; means movable with said pre-settable means and responsive to the movement of said member for effecting movement of said pre-settable means; and means rendered effective upon the actuation of any one of said control means for releasing said clamp means.

42. Apparatus comprising in combination, a member adapted to be moved in either direction along any one of a plurality of paths at any one of a plurality of feed speeds and at a relatively rapid traverse speed; a fluid-motor connected to said member for each path along which it is adapted to be moved; clamp means associated with each of said fluid motors and normally acting to prevent their movement; a plurality of means adapted selectively to be operated for controlling the admission of fluid to, and exhaust from selected sides of each of said fluid motors for moving said member in either direction at feed and traverse speeds along either of said paths; pre-settable means adapted upon movement to operate any of said control means; means movable with said pre-settable means and responsive to the movement of said member for effecting movement of said pre-settable means; and means rendered effective upon the actuation of any one of said control means for releasing the clamp means associated with the motor governed by said control means.

43. Apparatus comprising in combination, a member adapted to be moved in either direction along a path at any one of a plurality of speeds; a fluid motor for moving said member; means adapted selectively to be operated for controlling the admission of fluid to and exhaust from said fluid motor; means adapted to be pre-set for selectively operating one or more of a plurality of means including selected of said controlling means; means for indexing said pre-settable means from station to station; means responsive to the movement of said member for determining

when said indexing means is to be rendered effective; and means for indexing said determining means simultaneously with the indexing of said pre-settable means.

44. Apparatus comprising in combination, a member adapted to be moved in either direction along a path at any one of a plurality of speeds; a fluid motor for moving said member; a control member including specific portions adapted adjustably to support means for selectively controlling the admission of fluid to and exhaust from said fluid motor; means for controlling the effectiveness of said control member including a portion for each specific portion of said control member adapted adjustably to support means for controlling said control member; and means for maintaining said portions in exact phase relation at all times.

45. Apparatus comprising in combination, a member adapted to be moved in either direction along a path at any one of a plurality of speeds; a fluid motor for moving said member; a control member including a plurality of portions, each adapted selectively to be set for controlling the admission of fluid to and exhaust from said fluid motor; means for controlling the starting, stopping and duration of motion of said member including a plurality of portions, one for each of said control-member portions; and means for maintaining all of said portions in exact phase relation at all times.

46. Apparatus comprising in combination, a member adapted to be moved in either direction along a plurality of paths at any one of a plurality of speeds; fluid motors for moving said member along said paths; means adapted selectively to be operated for controlling the admission of fluid to and exhaust from said fluid motors; common means adapted to be pre-set for selectively

operating one or more of a plurality of means including selected of said controlling means; means for indexing said common pre-settable means from station to station; means responsive to the movement of said member along each of its paths for initiating the activity of said indexing means; and means for indexing said initiating means simultaneously with the indexing of said common pre-settable means.

47. Apparatus comprising in combination, a member adapted to be moved in either direction along a plurality of paths at a plurality of speeds; fluid motors for moving said member along each of said paths; a common control member including a plurality of portions, each adapted selectively to be set for controlling the admission of fluid to and exhaust from said fluid motors; separate means for each path along which said member is adapted to be moved for controlling the starting, stopping and duration of motion of said member along said path, each of said separate means including a plurality of portions, one for each of said control-member portions; and means for maintaining all of said portions in exact phase relation at all times.

48. In a fluid-motor apparatus of the class described, a control member including a plurality of portions, each adapted selectively to be set for causing said fluid-motor apparatus to produce any function of which it is capable; means for controlling the starting, stopping and duration of successive functions as dictated by the setting of successive portions of said control member, including a plurality of portions, one for each of said control-member portions; and means for maintaining all of said portions in exact phase relation at all times.

EDWARD P. BULLARD, III.

CERTIFICATE OF CORRECTION.

Patent No. 2,352,184.

June 27, 1944.

EDWARD P. BULLARD, III.

It is hereby certified that error appears in the printed specification of the above numbered patent requiring correction as follows: page 2, first column, line 18, after the word "spring" insert --collet--; page 8, first column, line 65, claim 7, strike out "direction"; page 11, second column, lines 18 and 19, claim 31, for "its control means for the" read --the control means for its--; and that the said Letters Patent should be read with this correction therein that the same may conform to the record of the case in the Patent Office.

Signed and sealed this 12th day of September, A. D. 1944.

Leslie Frazer

(Seal)

Acting Commissioner of Patents.
